LIQUID LEVEL CONTROL

Henry J. Rand, Bratenahl, Ohio; assignor to H. J. Rand Washing Machine Corp., Bratenahl, Ohio, a corporation of Delaware

Application January 31, 1948, Serial No. 5,620

1. Claim. (Cl. 68—21)

1

This invention relates to means for the control of a liquid level within a flexible bag.

One of the objects of the present invention is to provide a control member directly responsive to the pressure inside a flexible bag so that when the liquid within the bag reaches a predetermined level, the control member will be actuated.

Another object of the present invention is to provide a novel control member of the type described above wherein the column of liquid directly above the control member is effective over a relatively large area of the control member for producing its operation.

Another object of the present invention is to provide a hinged operator for the control member together with means for varying the relative position of the operating member and the control member so as to vary the predetermined level at which the control will be actuated.

Still another object of the present invention is to provide a control member, the operating condition of which will not flutter or fluctuate due to agitation of the liquid within the flexible bag.

Other objects and advantages of my invention will be apparent from the accompanying drawings and description and the essential features will be set forth in the appended claim.

In the drawings, Fig. 1 is a fragmental side elevational view of one embodiment of my invention with parts broken away to more clearly show the construction;

Fig. 2 is an enlarged fragmental section taken along the line 2—2 of Fig. 1;

Fig. 3 is a fragmental section through a modified form of my invention;

Fig. 4 is an enlarged fragmental sectional view showing a portion of Fig. 3;

Fig. 5 is an enlarged fragmental side elevational view taken generally along the position of the line 5—5 of Fig. 3;

Fig. 6 is a fragmental sectional view taken along the line 6—6 of Fig. 5;

Fig. 7 is a fragmental sectional view similar to Fig. 4 but showing another modification. This view is taken along the line 7—7 of Fig. 8;

Fig. 8 is a fragmental sectional view taken along the line 8—8 of Fig. 7; while

Fig. 9 is a fragmental sectional view taken in a position similar to Figs. 4 and 7 but showing still another modification of my invention.

While my invention is applicable to many different types of flexible containers, I have chosen to show my invention as applied to a washing machine of the type more fully shown and de-

scribed in my copending application Serial No. 5,619 filed January 31, 1948. Briefly, such a machine utilizes a flexible bag 10 of rubber or the like which is liquid and air tight and adapted to hold detergent up to the level of the line 11 of Fig. 1 during a washing operation. The side walls of the bag are supported by rigid tub walls 12 and the bottom of the bag is supported by the tub bottom 13. A cover 14 is provided for closing the normally open top of the bag during a washing operation. A seal is provided at the zone 15 where the cover meets the neck of the bag. This seal is adapted to close tightly when a vacuum is created within the bag as taught in my copending application. A pipe 16 is provided for introducing and withdrawing liquid inside the bag. Agitator means 17 is provided for agitating the clothes during a washing operation. The agitator is perforated as indicated at 18 for the flow of water into and out of the bag. The present invention is disclosed as a means for initiating a washing cycle when the water has filled to the predetermined level indicated at 11 in Fig. 1.

In the modification shown in Figs. 1 and 2, the control member indicated at 19 is an electrical switch although it will be understood by those skilled in this art that a mechanical control member might be operated if desired. The switch of the device in the casing 19 is provided with an operating stem 20 which in turn engages the projecting stem 21 of a large plate operator 22 which underlies the bottom wall of the flexible bag 10. In its normal or unoperated position the plate or cap 22 is raised as indicated in Figs. 1 and 2. It will be noted in Figs. 1 and 2 that the bottom wall 13 of the tub is depressed at 13a beneath the cap 22 so as to provide movement of the cap vertically downward. The entire device is supported by means of a fitting 23 which is provided with a shoulder 24 beneath the bottom wall 13a and a threaded nut 25 above the bottom wall portion which secures the device in position. The stem 21 is slidably mounted in the upper portion 23a of the member 23. A spring 26 biases the cap member 22 upwardly being held between a shoulder on the stem 21 and a cap 27 which is threaded on the member 23. A bracket 28 held between the shoulder 24 and the nut 25 serves to support the switch 19. The wires 29 lead away to a suitable control mechanism, which in the present instance is utilized to start the agitator 17 when the switch 19 is closed as fully described in my copending application.

It should now be obvious that the device of Figs. 1 and 2 will operate whenever the column of water over the area of the cap 22 is of sufficient weight to overcome the spring 26 so as to actuate the spring 19. The desired operating point may be chosen by regulating the area of the cap 22, the tension of the spring 26, and the relative position of the parts. It should be noted that the cap 22 is made convex upwardly so that the bottom of the flexible bag 10 will move smoothly backward and forward when the bag is collapsed and expanded as described in my co-pending application.

Another manner of applying my invention is clearly shown in Figs. 3 to 6 inclusive. Here the pressure switch is applied on one of the flexible side walls of the bag. A plate 30 of considerable area is secured to the rigid wall 12' which supports the flexible container by means of a suitable hinge permitting the plate to flex about its lower edge. In the present instance I have shown a hinge 31 of rubber or the like which is secured by suitable adhesive to the wall 12' and to the plate 30. It will be understood that the wall 12' is cylindrical and therefore this type of hinge is particularly adapted to this location. A switch 32 is mounted on a plate or bracket 33 which is secured to the rigid wall 12'. The switch operator 33a engages the plate 30. As clearly shown in Fig. 6, the free edge of the bracket 33 is held to the wall 12' by means of a screw 34. By adjusting the nut 35 the bracket 33 may be moved toward or away from the plate 30 so as to regulate the point at which the switch 32 will be operated.

The operation of the form of my device shown in Figs. 3 to 6 should now be apparent. When the liquid within the bag 101 rises to the level 11' as indicated in Figs. 3 and 4, the operating plate 30 will be moved from the full line position of Fig. 4 to the dot-dash line thereof so as to close the switch 32 and to actuate a circuit connected to lines 36 and 37. By placing the switch actuator 33a relatively near the hinge 31, the upper edge of plate 30 may be moved through a considerable distance without causing the switch 32 to flutter on and off. It will be understood that this is a great advantage in a washing machine supplied with an agitator like that shown at 11 where the movement of the water is likely to cause some movement of the plate 30.

In Figs. 7 and 8 I have shown a modification of the form of my invention just described. Here all of the parts which are the same have been given similar reference characters. The only difference is that the switch 38 is here shown as mounted on a bracket 39 in a manner to permit a vertical adjustment of the switch relative to the plate 30. Screws 40 pass through a slot 39a of the bracket and into the switch housing. By this means the switch may be moved up and down as desired so as to change the point at which the switch operator 38a engages the plate 30. This obviously will adjust the point at which the water level 11' operates the switch 38 and will regulate the sensitivity of the switch to the fluctuation of the plate 30.

In Fig. 9 I have shown still another modification of my invention utilizing a switch 41 which is of a type shown and described in United States Patent No. 1,780,758, granted November 4, 1930 to Henry G. Lupold. This switch has a blade 42 engaged by the switch actuator which is the

stem 43a of the operating button 43. It is characteristic of this switch that when motion of the actuator 43a has caused the switch 42 to flex from the position shown in Fig. 9 to engagement with the contact 44, considerable movement of the actuator 43a in the opposite direction is necessary to reverse the switch position. The switch is mounted in a bracket 45 which is secured to the rigid wall 120 which supports the side wall of the flexible bag 102. The large button head 43 lies back of the flexible wall 102. The position of the actuator 43a is adjustable by means of the nut 46.

The operation of the form of my device shown in Fig. 9 should now be clearly understood. When the liquid within the bag 102 arises to a sufficient level to press against the button head 43 it will operate the switch blade 42 so as to move the free end thereof from the position shown in Fig. 9 to a position in engagement with the contact 44. This will complete a circuit between the binding posts 47 and 48. One of the advantages of this form of my invention is that, once the liquid level has risen to a point sufficient to move the button head 43 toward the left as viewed in Fig. 9 sufficiently to cause blade 42 to engage contact 44, considerable fluctuation of the liquid within the flexible bag is necessary to cause sufficient retrograde movement of the operator 43a to permit the blade 42 to resume the position shown in Fig. 9. This device is therefore very useful in the case of my washing machine where in the liquid is agitated inside the bag 102.

What I claim is:

35 In combination, a washing machine comprising a flexible member to receive laundry and liquid and having a vertical side wall, means for admitting and discharging fluids to said container, an agitator within the container, means to actuate said agitator including a control switch member having an operator so arranged as to require appreciable movement between "on" and "off" positions, a plate engaging said operator, said plate having a pivotal mounting for movement in a substantially vertical plane, said plate lying outside of and positioned for engagement with said side wall, said operator being in operative engagement with said plate, whereby pressure of liquid in said container against the side wall will move said operator to its "on" position to actuate the agitator.

HENRY J. RAND.
